US00D605867S

(12) **United States Design Patent**
Lu

(10) **Patent No.:** US D605,867 S
(45) **Date of Patent:** ** Dec. 15, 2009

(54) **CHAIR**

(76) Inventor: **Shunjie Lu**, No. 86, Keyuancheng Industry Area, Tianxin Village, Tangxia Town, Dongguan City, Guangdong Province (CN) 523170

D446,661 S * 8/2001 Ambasz D6/368
D505,800 S * 6/2005 Lucci et al. D6/368
D558,999 S * 1/2008 Cantarutti D6/368

(**) Term: **14 Years**

* cited by examiner

(21) Appl. No.: **29/339,867**

Primary Examiner—Mimosa De
(74) *Attorney, Agent, or Firm*—Westman, Champlin & Kelly, P.A.

(22) Filed: **Jul. 9, 2009**

(57) **CLAIM**

(30) **Foreign Application Priority Data**

The ornamental design for a chair, as shown and described.

Mar. 13, 2009 (CN) 2009 3 0163983

DESCRIPTION

(51) **LOC (9) Cl.** **06-01**

FIG. 1 is a rear elevational view;

(52) **U.S. Cl.** **D6/368; D6/366**

FIG. 2 is a bottom plan view;

(58) **Field of Classification Search** D6/334-336, D6/368, 374, 376, 379, 380, 500-502; 297/40, 297/41, 55, 56, 58, 183.7, 411.2, 452.1, 452.29, 297/452.36

FIG. 3 is a top plan view;

See application file for complete search history.

FIG. 4 is a right elevational view;

(56) **References Cited**

FIG. 5 is a left elevational view;

U.S. PATENT DOCUMENTS

FIG. 6 is a front elevational view; and,

D440,784 S * 4/2001 Ambasz D6/368

FIG. 7 is a rear perspective view.
